UNITED STATES PATENT OFFICE.

JOHN F. CUNNEEN, OF CHICAGO, ILLINOIS.

FURNACE TRAVELING GRATE.

No. 916,112.

Specification of Letters Patent. Patented March 23, 1909.

Application filed September 27, 1905. Serial No. 280,389.

To all whom it may concern:

Be it known that I, JOHN F. CUNNEEN, a citizen of the United States, residing at Chicago, in the county of Cook and State of Illinois, have invented certain new and useful Improvements in Furnace Traveling Grates, of which the following is a specification.

This invention relates to furnaces and the object is to provide a furnace having a traveling grate so arranged that each tier of grate-bars will be automatically rocked at certain intervals as the grate moves toward the rear of the furnace; this operation will greatly assist in the combustion of coal for the reason that the coal will be stirred by the action of the grate-bars.

A further object of the invention is to provide a hopper which is provided with a series of plates and a screen so that when coal is placed into the hopper, the coarse coal will fall upon the traveling grate and the fine coal will pass through the screen and thence upon the coarse coal. This prevents the fine coal from falling through the grate-bars into the ash pit unconsumed, nor will it clog in the spaces between said grate-bars.

A still further object is to provide means whereby the speed of the traveling can be easily and conveniently regulated as desired.

In the accompanying drawings, Figure 1 is a longitudinal section of my improved traveling grate taken on line 1 1 of Fig. 2; Fig. 2 is an elevation of same, partly in section; Fig. 3 is a side view of same, with portions broken away, showing the operating mechanism; Fig. 4 is a detail plan view of the grate-bar and connecting links on enlarged scale; Fig. 5 is a side elevation of same, partly in section; Fig. 6 is an end view showing brace rods and sliding bar; Fig. 7 is an enlarged detail view of the contact bar; Fig. 8 is a front elevation of the screen showing it removed from the hopper and on a reduced scale.

Similar figures refer to similar parts throughout the several views.

The grate is mounted upon the movable frame 1 which is provided with wheels 2, said wheels rest upon a track 3. This allows the grate to be easily inserted into a furnace or removed therefrom. A series of brace rods 3^a extend through the lower portion of the frame 1, and are adapted to strengthen the side walls of said frame. A shaft 4 is journaled in the front end of frame 1, and mounted upon this shaft are sprocket wheels 5. The ends of shaft 6, in the rear end of the

frame 1, are mounted in bearing blocks 7, which slide longitudinally on guide brackets (not shown). An adjustable screw shaft 8 is secured to the bearing block 7 by means of which said bearing block carrying the shaft 6 may be moved longitudinally. Sprocket wheels 9 are rigidly secured on either end of the shaft 6. A drum (not shown) may be secured to the shaft 6 and the sprocket wheels 65 9 if desired.

The grate-bars 10 are formed substantially in the manner as shown in Fig. 7. These grate-bars are provided on the under side thereof with the projections 11 and 12, respectively. Said grate-bars are secured to transverse pivot rods 13 and are held in position thereon by means of cotter pins 14 passing through projections 11 and 12 and through pivot rod 13. The projections 11 and 12 are formed near one end of the grate-bars 10 thus causing said grate-bars to remain in a horizontal position, under normal conditions, when moving on the upper portion of the frame 1. A tube 10^a extends 75 from one side wall to the other of the frame 1 and a brace rod 12^a passes through the frame 1 and through the said tube. To the tube 10^a is rigidly secured, by means of clamp 13^a, bar 11^a. This bar extends longitudinally along the frame 1. The transverse pivot rods 13 slide upon the upper surface of this bar, thus preventing the traveling grate 20^a from sagging. On the outer ends of the pivot rods 13 are secured the link bars 90 15. These link bars hold the pivot rods 13 in position, forming the endless traveling grate 20^a. The transverse pivot rods 13 engage the sprockets in the sprocket wheels 5 and 9. 95

15^a indicates projections formed on the side walls of the frame 1, upon which the traveling grate 20^a will slide as said traveling grate moves toward the front of the furnace.

A contact bar 16 is pivotally secured to the frame 1 by means of a yoke 17. To the lower end of this bar is secured a lever 18 to which is pivotally secured one end of the rod 19. A projection 20 is formed in the frame 1 and acts as a stop against which the contact bar 16 will normally rest. The purpose of the contact bar is that when the traveling grate 20^a moves toward the rear end of the furnace, the projection 12 on the grate-bar 10 will come in contact with the contact bar 16, thus causing the grate-bar 10 to tip, as shown in Fig. 7 of the drawings. This will have a 100 105 110

tendency to break the coal which usually forms into a cake when in the heated furnace, especially when fine coal is used. After the projection 12 on the grate-bar 10 has passed the contact bar 16, by reason that said grate-bars are not centrally disposed on pivot rod 13, same will naturally assume a horizontal position. Furthermore, the weight of the coal on the grate-bars 10 will assist to cause said grate-bars to assume a horizontal position.

It will be readily understood that any number of contact bars 16 may be employed. If it is desired not to use the contact bar 16 the same may be placed out of operation by pushing the rod 19 backward and causing said contact bar to assume the position as shown in dotted lines in Fig. 7 of the drawings.

20 A self dumping grate 21 is secured in the rear end of the frame 1. Pivot bolts 22 are formed on the side of said grate 21 and rest in bearings 23. The rear end of the grate 21 is bent at right angles and rests upon projection 24, and is so arranged as to assume a horizontal position under normal conditions. When, however, sufficient ashes and the like have been deposited upon the grate 21 to cause same to become overbalanced said 30 grate will tip, thus depositing the contents thereon in the ash pit.

The fire door 25 may be of the usual construction and raised and lowered by means ordinarily used for that purpose. A plate 26 35 is secured in the front end of the frame 1, this plate holds the coal in position where it can be readily conveyed by the traveling grate 20^a to the fire. The lower plate 27 is held in position in the frame 1 by means of 40 guideways 27^a. From the front end of this plate extends screen 28. This screen is held in position in the frame 1 by means of projections (not shown) extending from the side walls of said frame. An upper plate 29 is 45 held in position in the frame 1 by means of the guideways 30.

Shaft 4 is provided on one end thereof with gear wheel 31. This gear wheel meshes with worm gear 32, secured to shaft 33. Said 50 shaft 33 is journaled in bearings 34, secured to the frame 1, and a ratchet wheel 35 is secured on one end of said shaft.

One end of the bracket 36 is pivotally secured to the frame 1 and the opposite end 55 thereof engages reciprocating rod 37. A pawl 38 is secured to this bracket and engages the ratchet wheel 35. One end of bracket 39 is rigidly secured to the frame 1 and the opposite end thereof loosely engages the lower end 60 of reciprocating rod 37. An adjusting rod 40 passes through bracket 39, and regulates the speed of the worm gear 32. To obtain a change of speed the adjusting rod 40 is pushed upward until the upper end thereof engages 65 bracket 36. The adjusting rod 40 may be

locked in position by means of the locking pin 41. The collar 42 on the reciprocating rod 37 is for the purpose of allowing bracket 36 to rest thereon when the adjusting rod 40 is not in contact therewith. The reciprocating rod 37 is driven by any suitable power. As the reciprocating rod 37 is moved upward the collar 42 will come in contact with the bracket 36 and move said bracket upward and the pawl 38 engages the ratchet wheel 35 75 which is rigidly secured to the shaft 33, this will cause said shaft carrying the worm gear 32, to rotate, and moving gear wheel 31.

The advantages of this furnace are as follows: When coal is placed upon the plate 29 80 same will pass therefrom and on to screen 28. The coarse coal will fall on to the grate-bars 10 and the fine coal will pass through the screen 28; it will thus be apparent that the coarse coal will always rest upon the grate 85 and the fine coal upon the coarse coal, and that all the fine coal will be consumed and will not clog or fall between the grate-bars 10. When the projection 12 on the grate-bar 10 strikes the contact bar 16, one end of 90 said grate-bar will tip upward thus breaking the fuel which usually forms into a solid mass, and also allows air to come up from underneath the fire and insure perfect combustion. As the grate moves toward the rear end of 95 the furnace the ashes and the like will be deposited upon the dumping grate 21 and the particles of coal remaining unconsumed will be consumed, and when a certain amount of ashes and the like have been deposited upon 100 said dumping grate same will tip and deposit the contents thereon in the ash pit. A further purpose of the dumping grate is to exclude air from reaching the fire from the rear end of the furnace.

105 A further advantage of my arrangement of the grate-bars 10 is, that in returning to the front end of the furnace same assumes an inclined position, thus allowing the air from the bottom of the furnace to circulate there- 110 through.

Another important feature of my invention is the mechanism for operating the traveling grate. By means of this arrangement I am able to obtain a fast speed or a slow speed 115 for the traveling grate, as is best desired.

With slight modifications in construction this traveling furnace grate may be used to advantage in marine and locomotive boiler furnaces.

120 Slight changes can of course be made in the general form and arrangement of the several parts herein described without departing from the spirit and scope of my invention, hence I do not wish to be limited to the exact construction herein set forth.

What I claim as new and desire to secure by Letters Patent, is—

1. In a furnace of the class described, the combination of a grate receiving frame hav- 130

- ing shafts journaled in the front and rear ends thereof, sprocket wheels secured to said shafts, a traveling grate composed of a plurality of transverse pivot rods, links connecting the ends of said rods, grate bars provided with a projection on the under surface secured to said pivot rods, said pivot rods being supported by the sprocket wheels, contact bars pivotally secured to the main frame against which the projections underneath the grate bars will strike as the traveling grate moves toward the rear of the furnace thus tilting the grate bars, substantially as described.
- 15 2. In a furnace of the class described, the combination of a grate receiving frame having shafts mounted in the front and rear ends thereof, sprocket wheels secured to said shafts, a traveling grate composed of a plurality of transverse pivot rods, links connecting said rods, grate bars provided with a projection on the under surface secured to said pivot rods, contact bars pivotally secured to the main frame against which the 20 projections underneath the grate bars will
- strike as the traveling grate moves toward the rear of the furnace, means for throwing said contact bar out of operation, a worm gear transmission operated by means of an actuating rod for rotating the shaft in the front end of the furnace, and means for regulating the speed of said shaft, substantially as described.
- 10 3. In a furnace of the class described, the combination of a grate receiving frame, a feed hopper in the front end thereof, an inclined plate extending from the front toward the rear of the hopper, an inclined screen extending from the rear of the hopper forwardly beneath the plate and spaced therefrom, a plate upon which the forward end of the screen rests, said plate inclined rearwardly, substantially as described.
- 15 In testimony that I claim the foregoing as my invention I have signed my name in presence of two subscribing witnesses.
- 20 JOHN F. CUNNEEN.
